UNITED STATES PATENT OFFICE.

EMMETT F. CARTER, OF SCHENECTADY, NEW YORK, ASSIGNOR TO GENERAL ELECTRIC COMPANY, A CORPORATION OF NEW YORK.

HIGH-FREQUENCY DUPLEX SIGNALING SYSTEM.

Application filed January 27, 1925. Serial No. 5,148.

My present invention relates to signaling systems adapted to duplex operation, and more particularly to high frequency signaling systems of the carrier current type.

5 One of the objects of my invention is to provide a system whereby duplex operation may be carried on by the use of a single high frequency for the carrier currents transmitted in both directions.

10 Another object of my invention is to provide a transmitting apparatus which will be operative only when a signaling potential is impressed thereon.

15 Still another object of my invention is to provide means whereby both a transmitting apparatus and a sensitive receiving apparatus may be simultaneously coupled to a signaling circuit without injury to the receiving apparatus when the transmitting apparatus is 20 in operation.

The novel features which I believe to be characteristic of my invention are set forth with particularity in the appended claims. My invention itself, however, both as to its 25 organization and method of operation, will best be understood by reference to the following description taken in connection with the accompanying drawing, on which I have shown diagrammatically one circuit organization which may be used in carrying my invention into effect.

I have indicated in the drawing the application of my invention to a duplex carrier current telephone system for communication over a circuit which is merely indicated by the conductor 1. The circuit may be an ordinary communication circuit, or a power line, or it may be a radio transmitting circuit. The transmitting apparatus comprises a 35 three-electrode electron discharge tube 2, which serves as a generator of oscillations, an amplifying tube 3 which serves to amplify the oscillations produced by tube 2, a modulating tube 4 which serves to modulate the 40 amplified oscillations of tube 3, an amplifying tube 5 for amplifying speech currents produced by telephone transformer 6 and supplying the amplified speech currents to the input or control circuit of modulator 4, and 45 control tubes 7 and 8 for controlling the operation of oscillator 2.

The cathodes of all of the tubes mentioned are connected in parallel and supplied with heating current from an alternating current 50 source 9 through a transformer 10. Plate

circuits of tubes 2, 3, 4, and 5 are supplied with current from sources 11, 12, and 13. Plate circuits of tubes 7 and 8 are supplied with alternating current from the source 9 through a transformer having primary winding 14 and secondary windings 15 and 16, so connected that the plates of both tubes are positive or negative at the same times. The plate circuit of control tube 7 includes the resistance 17, which is also included in the 60 grid circuit of oscillator 2. The plate circuit of tube 8 includes a resistance 18, a portion of which is connected in the grid circuit of tube 7.

The grids of modulator tube 4 and control tube 8 are connected together and are normally biased negatively by the source 19. When no signaling current is impressed upon the system the voltage of the source 19 is so chosen that substantially no current will 70 flow in the plate circuit of tube 8. As a result the grid of tube 7 will be of substantially cathode potential and current will flow in the plate circuit of tube 7 of such a value as to produce a voltage drop through resistance 17 of such value as to provide a negative bias on the grid of oscillator 2 high enough to prevent the production of oscillations. 75

When speech currents are produced by microphone 6 the output of amplifying tube 5 is supplied through transformer 20 to the grids of tubes 4 and 8. As a result, the grid of tube 8 will become sufficiently positive to permit current to flow in its plate circuit. This will result in the production of a negative bias on the grid of tube 7, which will cut 80 down the current in its plate circuit, and also reduce the negative bias on the oscillator grid sufficiently to permit the production of oscillations. The oscillations produced will 85 be modulated by the action of tube 4 in a well known manner.

While the plate circuits of tubes 7 and 8 are supplied with alternating potential, the condensers 21, 22 have sufficient storage capacity to prevent the voltages applied to the grids of tubes 2 and 7 falling at any time below the cutoff value. By means of these condensers the potential on the grid of the device 2 is smoothed sufficiently to prevent 90 any substantial modulation of the currents produced by the oscillator in accordance with voice currents, the necessary modulation of the high frequency wave being effected by the device 4. 100

I have found in actual operation that the operation of the system described is substantially instantaneous, particularly if alternating current source 9 is of a frequency about 5 equal to the normal voice frequency and that transmission starts at almost the same instant that a signaling current starts in the microphone.

For reception the receiving circuit may be 10 coupled to the transmitting circuit through a coupling transformer 23, the secondary of which is included in a tuned link circuit 24. This link circuit, in turn, is coupled to a tuned circuit 25, which may be connected to any desired form of receiver. To protect the receiving apparatus from the effect of potentials which may be impressed thereon by the transmitting apparatus when the latter is in operation, I provide in shunt to the link 15 circuit 24, a path which offers a substantially infinite impedance to the received currents, but a comparatively low impedance to currents impressed upon the link circuit 18 from the transmitting apparatus. This device as 20 indicated in the drawing consists of an electron discharge tube 26 having its grid and anode connected together and made slightly negative by battery 27. When signaling currents are being received the impedance of 25 tube 26 is practically infinite; hence, the operation of the receiving system is not interfered with in any way. When, on the other hand, the transmitter is operating and a high voltage is impressed upon the link circuit 30 24; the anode of tube 26 will become positive, consequently, its impedance will be greatly reduced. As a result, a large portion of the energy impressed upon the link circuit will be shunted through tube 26, thus partially 35 detuning the link circuit and increasing its impedance, thereby greatly reducing the potential impressed upon the receiving apparatus. By this expedient I have found that 40 the receiving apparatus will be effectively 45 protected from injury and that it will always be in condition to receive and indicate received signals as soon as the transmitting apparatus has ceased operation.

While I have shown and described the apparatus required for one end of a duplex signaling circuit, it will, of course, be understood that the apparatus at the opposite end may be an exact duplicate of that shown and described. It will also be apparent that the system shown and described will be adapted to any form of high frequency signaling desired, either over wire lines or radio, and for telegraphic signaling, as well as telephonic.

What I claim as new and desire to secure by Letters Patent of the United States, is,—

1. In a transmitting apparatus for a high frequency signaling system comprising an electron discharge oscillator, a control device 65 for said oscillator comprising means for nor-

mally providing a negative bias on the grid of said oscillator sufficient to prevent the production of oscillations and means responsive to an audio frequency signaling current for reducing the negative bias to a value at which 70 oscillations will be produced, the bias potential being sufficiently smoothed substantially to prevent modulation by voice currents of the oscillations produced.

2. In a transmitting apparatus for a high 75 frequency signaling system comprising an electron discharge oscillator, a control device for said oscillator comprising means comprising a second electron discharge device for normally providing a negative bias on the 80 grid of said oscillator sufficient to prevent the production of oscillations and means responsive to signaling current for controlling the current through said second device and thereby reducing the negative bias of the oscillator grid to a value at which oscillations will be produced, the bias potential being sufficiently smoothed substantially to prevent modulation by voice currents of the oscillations produced.

3. A transmitting apparatus for a high 85 frequency signaling system comprising an electron discharge oscillator, a second electron discharge device having included in its 90 plate circuit a resistance which is included 95 in the grid circuit of the oscillator, said second device being normally so adjusted that the current flowing in its plate circuit will produce a negative bias on the grid of the oscillator sufficient to prevent the production 100 of oscillations and means responsive to signaling current for controlling the current through said second device and thereby reducing the negative bias of the oscillator grid to a value at which oscillations will be produced, the bias potential being sufficiently smoothed substantially to prevent modulation by voice currents of the oscillations produced.

4. A transmitting apparatus for a high 105 frequency signaling system comprising an electron discharge oscillator, means comprising a second electron discharge device for normally providing a negative bias on the 110 grid of the oscillator sufficient to prevent the production of oscillations and a third electron discharge device for controlling the current through the second device and thereby reducing the negative bias of the oscillator 115 grid to a value at which oscillations will be produced, said third device being controlled 120 in its action by the signaling current to be transmitted.

5. A transmitting apparatus for a high 125 frequency signaling system comprising an electron discharge oscillator, a second electron discharge device having included in its plate circuit a resistance which is included in the grid circuit of the oscillator, said second 130

device being normally so adjusted that the current flowing in its plate circuit will produce a negative bias on the grid of the oscillator sufficient to prevent the production of oscillations, and a third electron discharge device for controlling the current through the second device and thereby reducing the negative bias of the oscillator grid to a value at which oscillations will be produced, said 10 third device being controlled in its action by the signaling current to be transmitted.

6. A transmitting apparatus for a high frequency signaling system comprising an electron discharge oscillator, a second electron discharge device having included in its plate circuit a resistance which is included in the grid circuit of the oscillator, said second device being normally so adjusted that the current flowing in its plate circuit will 20 produce a negative bias on the grid of the oscillator sufficient to prevent the production of oscillations, and a third electron discharge device having included in its plate circuit a resistance which is also included in the grid circuit of the second device, said third device being controlled by the signaling current to be transmitted in such a way that application of the signaling current thereto will cause the negative bias of the oscillator grid to be reduced to a value at which oscillations will 25 be produced.

7. A transmitting apparatus for a high frequency signaling system comprising an electron discharge oscillator, a second electron discharge device having included in its plate circuit a resistance which is included in the grid circuit of the oscillator, said second device being normally so adjusted that the current flowing in its plate circuit will 35 produce a negative bias on the grid of the oscillator.

40

cillator sufficient to prevent the production of oscillations, and a third electron discharge device having included in its plate circuit a resistance which is also included in the grid circuit of the second device, said third device 45 having its grid normally biased to a negative value sufficient to substantially prevent the flow of current in its plate circuit and being controlled by the signaling current to be transmitted in such a way that the application of a signaling current thereto will cause the negative bias of the oscillator grid to be reduced to a value at which oscillations will 50 be produced.

8. A transmitting apparatus for a high frequency signaling system comprising an electron discharge oscillator, a second electron discharge device having included in its plate circuit a resistance which is included in the grid circuit of the oscillator, said second device being normally so adjusted that the current flowing in its plate circuit will produce a negative bias on the grid of the oscillator sufficient to prevent the production 55 of oscillations, and a third electron discharge device having included in its plate circuit a resistance which is also included in the grid circuit of the second device, said third device having its grid normally biased to a negative 60 value sufficient to substantially prevent the flow of current in its plate circuit and being controlled by the signaling current to be transmitted in such a way that application of the signaling current thereto will cause a negative bias to be produced on the grid of 65 the second device.

In witness whereof, I have hereunto set my hand this 26th day of January, 1925.

EMMETT F. CARTER.
